UNITED STATES PATENT OFFICE.

ALFRED L. BROUILLETTE, OF CAMPBELL, NEBRASKA, ASSIGNOR OF ONE-HALF TO
ROMULUS C. CHEVALIER.

HOIST.

1,140,440.

Specification of Letters Patent. Patented May 25, 1915.

Application filed February 17, 1914. Serial No. 819,230.

To all whom it may concern:

Be it known that I, ALFRED L. BROUILLETTE, a citizen of the United States, residing at Campbell, in the county of Franklin 5 and State of Nebraska, have invented a new and useful Hoist, of which the following is a specification.

The device forming the subject matter of this application is a hoist, adapted to be 10 employed for handling automobiles and other heavy objects.

One object of the present invention is to provide novel means for procuring relative movement between the fixed and movable portions of the supporting frame.

Another object of the invention is to provide a hoisting mechanism of novel form.

The invention aims to provide a structure of the type described which will possess unusual strength and be well adapted 20 to withstand the severe usage to which hoists of this type are subjected.

It is within the scope of the invention to improve generally and to enhance the utility 25 of devices of that type to which the present invention appertains.

With the above and other objects in view which will appear as the description proceeds, the invention resides in the combination 30 and arrangement of parts and in the details of construction hereinafter described and claimed, it being understood that changes in the precise embodiment of the invention herein disclosed can be made 35 within the scope of what is claimed without departing from the spirit of the invention.

In the accompanying drawings:—Figure 1 shows the invention in side elevation, parts being broken away; Fig. 2 is a top plan; 40 Fig. 3 is a side elevation; Fig. 4 is an enlarged detail taken from Fig. 1, portions of the hoisting drum being broken away; Fig. 5 is a transverse section taken through portions of the main and auxiliary frames; 45 Fig. 6 is a sectional detail of one of the dogs; Fig. 7 is a fragmental elevation illustrating a portion of one dog and attendant parts.

In carrying out the present invention there is provided a main frame which, in 50 its turn, comprises a pair of supports denoted generally by the numeral 1. Each support 1 comprises a horizontal foot 2 provided with casters 2a. Fixed to and rising from each foot 1 intermediate the 55 ends thereof is a standard 3. Located upon

each side of the standard 3 are abutments 4 which may be angle brackets, the abutments 4 being secured to the supports 1. Securing elements 5 unite the abutments 4 with each foot 2. Each standard 3 is sustained by 60 means of short, upwardly converging braces 6 and longer, upwardly converging braces 7. The lower ends of the braces 6 and 7 are superposed and are held upon the foot 2 by means of the securing elements 8, the upper 65 ends of the braces 6 and 7 being secured to the standard 3.

The invention further includes a U-shaped auxiliary frame 9, mounted to move vertically. The U-shaped frame 9 comprises upright arms 10, to the upper ends of which are secured spaced top bars 11, the top bars being connected with the arms by means of braces 12. Struts 14 are mounted between the top bars 11 and receive the intermediate 70 portions of the truss rods 15, the ends of which pass through plates 16 bearing against the ends of the top bars 11, the terminals of the truss rods 15 carrying nuts 17 which engage the plates 16.

The arms 10 of the U-shaped auxiliary frame 9 are held in sliding contact with the standards 3 by means of guides 18 and 19. The guides 18 are located adjacent the upper ends of the standards 3 and are terminally secured thereto, these guides extending around the inner edges of the arms 10 of the U-shaped frame 9. The guides 19 are located adjacent the lower ends of the arms 10 of the U-shaped frame 9 and are secured thereto, the last mentioned guides passing around the outer edges of the standards 3. By the construction above described, the U-shaped frame 9 is connected 80 with the supports 1 of the main frame for 90 vertical movement.

A means is provided for positively holding the U-shaped frame 9 in different positions of vertical adjustment. With this end in view, shafts 20 are journaled for rotation 100 in the arms 10 of the auxiliary frame 9. Each shaft 20 is provided at one end with a dog 21. The dogs 21 are identical in form with dogs 23 to be described hereinafter. The other end of the shaft 20 is squared as 105 indicated at 22 and is received within a recess formed in the dog 23. A bolt 24 or other securing element passes through the shaft 20 and upon the end of the bolt 24 there is a nut 25 which engages the dog 23 110

to hold the same in place. Projecting from the opposite sides of each standard 3 are pins 26. Each dog 23 is hooked slightly as indicated at 27, so as to coöperate with one of the pins 26, and in this manner, downward movement of the U-shaped auxiliary frame 9 is prevented. The outer or terminal edges of the dogs 23 are cam-shaped as indicated at 28. Downward movement of the dogs 21 and 23 is limited by means of a stop pin 29 which projects from the arm 10 of the auxiliary frame 9. If desired, one dog may be engaged by a spring 30 secured to the arm 10, the function of the spring 30 being to maintain the dog yieldably engaged with the stop pin 29.

When the U-shaped auxiliary frame 9 is raised by a mechanism to be described hereinafter the dogs 21 and 23 will be raised also and shifted out of engagement with certain of the pins 26. The cam 28 on the dogs will engage the next upper set of pins, and thus the dogs will be tilted inwardly and, ultimately, will engage again with a pair of pins 26.

A means is provided for raising and lowering the U-shaped auxiliary frame 9 and, with this end in view, racks 31 are secured to the arms 10 of the frame 9. These racks 31 coat with pinions 32 secured to shafts 33 mounted in brackets 34 of U-form, the brackets 34 embracing the standards 3 and the arms 10 of the auxiliary frame 9, the brackets, however, being secured to the standards 3. Each shaft 33 is actuated by means of a crank 35, adjustably and removably held in place by means of a set screw 36 or the like.

Secured to one of the standards 3 is a bracket 37, sustained by means of downwardly converging braces 38, the lower ends of which are connected with the securing elements 5 which, it will be recalled, serve to hold the abutments 4 in place on the foot 2. Journaled for rotation in the bracket 37 is a shaft 39 provided at one end with a crank 40. Mounted upon and secured to the shaft 39 between the drum 41 is a ratchet 42 adapted to coat with a pawl 43, pivoted as indicated at 44 to arms 45 projecting from the standard 3. The pawl 43 is manipulated by means of a handle 46 thereon, and the pawl is yieldably held in engagement with the ratchet 42 by means of a retractile spring 47, one end of which is secured to the pawl, the other end of which is secured to the standard 3.

The hoisting mechanism comprises a primary pulley 48 and a secondary pulley 49, mounted to rotate between the top bars 11 of the auxiliary frame 9 and located adjacent one of the standards 3. A primary pulley 50 and a secondary pulley 51 are similarly journaled between the top bars and are

located adjacent the other standard 3. The pulley 51 preferably is provided with a double tread for a purpose which will be set forth hereinafter. The invention includes a pulley block 52 and a flexible element 53 which is carried upwardly around the pulley 48 and thence is carried downwardly through the block 52 and upwardly around the pulley 49. From the pulley 49, the flexible element 53 passes across the pulley 51 and is engaged in one of the treads thereof. From the pulley 51, the flexible element 53 is carried downwardly and is attached to one of the winding drums 41.

Another pulley block 55 is provided, and to this pulley block 55 is secured a flexible element 56, carried upwardly around the pulley 50 and downwardly through the block 55, the flexible element being carried over the other tread on the pulley 51 and thence being carried downwardly into operative connection with the other drum 41.

It will be obvious that when rotation is imparted to the shafts 33 by means of the cranks 35, the pinions 32, coating with the racks 31, will serve to raise and lower the auxiliary frame 9. During this operation, the dogs 23 and 21 on the respective arms 10 of the frame 9 will engage automatically with one set after another of the pins 26 on the standards 3 and thus hold the U-shaped frame 9 in adjusted positions vertically.

When the shaft 30 is manipulated by means of the crank 40, both of the drums 41 will be rotated and the flexible elements 53 and 56 will be reeled in together, thus simultaneously elevating the blocks 55 and 52.

It will be understood that any number of sheaves may be located in the blocks 55 and 52, the pulleys upon the U-shaped frame 9 being increased in number accordingly, this construction being a detail well within the scope of any skilled mechanic.

The pawl 43 is spring constrained to coöperate with the ratchet 42, thereby holding the tension which has been secured in the flexible elements 56 and 53. However, through the medium of the handle 46, the pawl 43 may be released from the ratchet 42, thus permitting the object which is assembled with the pulley blocks 52 and 55 to be shifted.

Having thus described the invention, what is claimed is:—

In a device of the class described, a main frame comprising supports; a U-shaped auxiliary frame comprising arms slidable upon the supports; a plurality of superposed projections on the supports; pivot elements on the arms and disposed out of vertical alignment with the projections; upwardly extended, laterally inclined pawls carried by the pivot elements, the pawls including hooks adapted to engage automatically with the projections, and cams adapted to engage

the projections and to tilt the pawls, thereby to disengage the hooks from the projections when the auxiliary frame is raised; rocks on the arms; shafts on the supports; 5 pinions on the shafts and engaging the racks; and a hoisting mechanism on the auxiliary frame.

In testimony that I claim the foregoing as my own, I have hereto affixed my signature in the presence of two witnesses.

ALFRED L. BROUILLETTE.
